UNITED STATES PATENT OFFICE.

CHARLES F. STODDARD, OF BOSTON, MASSACHUSETTS, ASSIGNOR TO AMERICAN PNEUMATIC SERVICE COMPANY, OF DOVER, DELAWARE, A CORPORATION OF DELAWARE.

CARRIER FOR PNEUMATIC-DESPATCH-TUBE APPARATUS.

No. 842,354.

Specification of Letters Patent.

Patented Jan. 29, 1907.

Application filed May 20, 1904. Serial No. 208,812.

To all whom it may concern:

Be it known that I, CHARLES F. STODDARD, of Boston, in the county of Suffolk and State of Massachusetts, have invented certain new and useful Improvements in Carriers for Pneumatic-Despatch-Tube Apparatus, of which the following is a specification.

My invention relates to certain new and useful improvements in carrier-locks for pneumatic-despatch apparatus, and especially to carriers for large-sized tubes for carrying mail-matter, merchandise, and the like.

The object of my invention is to produce a lock which is simple in construction and will not allow the cover to open after the carrier is inserted into the tube.

My invention consists of certain novel features hereinafter described, and particularly pointed out in the claims.

In the accompanying drawings, which illustrate a construction embodying my invention, Figure 1 is an end elevation of the inner end of the carrier, showing the cover and the locking mechanism in their normal locked positions. Fig. 2 is a similar view of the carrier and cover, but showing the safety-lever swung out. Fig. 3 is a similar view of the cover and carrier, but showing the parts in their unlocked position. Fig. 4 is a sectional view on the line X Y Z, Fig. 3, through one end of the carrier and showing the parts of the locking device unlocked, as shown in Fig. 3. Fig. 5 is a sectional view on the line X Y Z, Fig. 1, showing the parts of the locking device in their locked position, as in Fig. 1.

Like letters of reference refer to like parts throughout the several views.

A represents the shell of a carrier, the top of which is reinforced by the band A'. To the shell A by means of the hinge A² is pivoted the cover A³. The upper portion of the cam-bolt A⁴ is securely fastened to the lever A⁵ at A⁶ in such a way that the cam-bolt A⁴ may be swung around by the lever A⁵. The safety-lever A⁷ is pivotally connected to the cover A³ at A⁸ in such a way that it can swing freely about the pivot. The portions of the locking-lever A⁵ and the safety-lever A⁷ immediately around their pivots are shaped so as to form an interlocking device, so that it is possible to swing the lever A⁵ only when the

lever A⁷ is in the position shown in Fig. 3 and possible to swing the safety-lever A⁷ only when the lever A⁵ is in the position shown in Fig. 1.

The cam portion B of the cam-bolt A⁴ is shown by dotted lines in Figs. 1, 2, and 3. It is so shaped that the side B' will not extend into the slot B³ in the shell A when said cam-bolt A⁴ is in the position shown in Figs. 4 and 60 3, in which position the cover A³ is not locked to the shell A. When the cam-bolt A⁴ is swung into the position shown in Figs. 1 and 55 5, the cam portion B extends into the slot B³ B² of the shell A and the cover A³, respectively, and also extends through the slot B⁴ in the reinforcing-plate A, Fig. 5.

In Fig. 3, which shows the locking parts in their positions when the cover A³ is not locked to the shell A, it will be seen that the lever A⁵ 70 can be freely moved into the position shown in Fig. 2; but the safety-lever A⁷ cannot be moved from the position shown in Fig. 3. The convex rounding portion C of the lever A⁵ and the concave rounding portion C' of 75 the lever A⁷ are concentric with the pivot A⁶, upon which the lever A⁵ swings. This arrangement makes it impossible to swing the safety-lever A⁷ into the position shown in Fig. 1 until the lever A⁵ is swung into the position shown in Fig. 2, which brings the concave rounding portion C' of the lever A⁵ concentric with the pivot A⁸, upon which the safety-lever A⁷ swings. The convex rounding portion C² of the safety-lever A⁷ is concentric with the pivot A⁸, upon which the safety-lever A⁷ swings, and constructed to mesh with the concave rounding portion C² of the lever A⁵ when said lever A⁵ is in the position shown in Fig. 2, so that it is possible with 90 the lever A⁵ in this position, Fig. 2, to swing the safety-lever A⁷ into the position shown in Fig. 1. This safety-lever A⁷ is pivoted near the periphery of the cover A³, so that when it is swung into the position shown in Fig. 3 95 it extends beyond the circumferential limits of the carrier and makes it impossible to insert the carrier into the transmission-tube and also makes it impossible for the lever A⁷ to be swung from the position shown in Fig. 1 to that shown in Fig. 2 while the carrier is 100 in the transmission-tube.

As before explained, when the cover A³ is unlocked from the shell A the parts are in the position shown in Fig. 3 and the cycle of operation of the lock is as follows: The cover A³ being swung upon the hinge A² into its closed position, (shown in Fig. 4,) the lever A⁵ is moved into the position shown in Fig. 2, the motion being limited by the shoulder S, which engages the safety-lever A⁷ when the proper position of the lever A⁵ is reached. Then the safety-lever A⁷ is swung into the position shown in Fig. 1, leaving the carrier locked and ready for transmission. As before explained, when the lever A⁵ is swung from the position shown in Fig. 3 to that shown in Fig. 2 the cam-bolt A⁴, being securely fastened thereto, swings with the lever A⁵, and the cam portion B swings into the slots B² B³ B⁴. The button D is riveted to the cover A³ in such a position that when the safety-lever A⁷ is swung into the position shown in Fig. 1 it springs over the same and is held in that position. In unlocking cover it is necessary to swing the safety-lever A⁷ from the position shown in Fig. 1 into that shown in Fig. 2 before the lever A⁵ can be moved from the position shown in Fig. 1 to that shown in Fig. 3, because the convex rounding portion C³ of the safety-lever A⁷ is meshed with the concave rounding portion C² of the lever A⁵. After the safety-lever A⁷ is swung from the position shown in Fig. 1 to that shown in Fig. 2 the lever A⁵ is swung from the position shown in Fig. 1 to that shown in Fig. 3, and thereby locks the safety-lever A⁷ into the position shown in Fig. 3, because the convex rounding portion C of the lever A⁵ is meshed with the concave rounding portion C' of the safety-lever A⁷. The shoulder S' on the safety-lever A⁷ limits the motion of the safety-lever A⁷ when it is swung from the position shown in Fig. 2 to that shown in Fig. 1. When the safety-lever A⁷ is swung from the position shown in Fig. 1 to that shown in Fig. 2, the portion S² engages the shoulder S of the lever A⁵, thereby limiting the swing of the safety-lever A⁷ in this direction. The motion of the lever A⁵ in swinging it from the position shown in Fig. 2 to that shown in Fig. 3 is limited by the portion S¹ engaging the convex rounding portion C³ of the safety-lever A⁷.

I do not limit myself to the arrangement and construction shown, as the same may be varied without departing from the spirit of my invention.

Having thus described the nature of my invention and set forth a construction embodying the same, what I claim as new, and

desire to secure by Letters Patent of the United States, is—

1. In a carrier for pneumatic-despatch-tube apparatus, a shell, a cover hinged to said shell, a bolt for locking said cover to the shell, a pivoted member for operating said bolt and a second pivoted member for securing the first-mentioned pivoted member; each of said pivoted members having a surface concentric with its own pivotal point and a surface concentric with the pivotal point of the other member; and said pivoted members operating so that neither can be turned except when concentric surfaces register with each other.

2. In a carrier for pneumatic-despatch-tube apparatus, a shell, a cover hinged to said shell, a bolt for locking said cover to the shell, a pivoted lever for operating said bolt, and a safety-lever pivoted on said cover; each of said levers having a surface concentric with its pivotal point and a surface concentric with the pivotal point of the other lever; and said levers operating so that neither can be turned except when concentric surfaces register with each other.

3. In a carrier for pneumatic-despatch-tube apparatus, a shell, a cover hinged to said shell, a bolt for locking said cover to the shell, a pivoted member for operating said bolt and having a curved surface concentric with its pivotal point, and a second pivoted member having a curved surface concentric with the pivotal point of the pivoted member for operating the bolt; and said pivoted members operating so that the bolt-operating member cannot be turned except when the two concentric surfaces register with each other.

4. In a carrier for pneumatic-despatch-tube apparatus, a shell, a cover hinged to said shell, a bolt for locking said cover to the shell, and mechanism for securing said bolt comprising two pivoted members with one of said pivoted members operating to move the bolt; both of said pivoted members having curved surfaces concentric to the pivotal points of each of said members; and said members operating so that neither can be turned except when concentric surfaces register with each other.

In testimony whereof I have signed my name to this specification, in the presence of two subscribing witnesses, this 14th day of May, A. D. 1904.

CHARLES F. STODDARD.
